UNITED STATES PATENT OFFICE.

EDWARD F. GOLTRA, OF ST. LOUIS, MISSOURI.

CAR-TRUCK SIDE FRAME.

SPECIFICATION forming part of Letters Patent No. 620,911, dated March 14, 1899.

Application filed November 9, 1896. Serial No. 611,545. (No model.)

To all whom it may concern:

Be it known that I, EDWARD F. GOLTRA, a citizen of the United States, residing at St. Louis, in the State of Missouri, have invented 5 certain new and useful Improvements in Car-Truck Side Frames; and I do hereby declare the following to be a full, clear, and exact description of the invention, such as will enable others skilled in the art to which it applies to make and use the same.

In the present invention I provide for the ready removal of the axle-boxes and connect the transom channel-beams directly to the inner side of the journal-bar, which in such 15 case I preferably form of greater depth in its middle than at its ends, and I preferably further strengthen and support the structure by carrying the tie-bar upward and joining its middle portion to the lower flange of the journal-bar.

In the drawings, Figure 1 represents in side elevation a car-truck side frame embodying my invention. Fig. 2 represents a top plan view thereof, partly in section. Fig. 3 represents a section on the line 3-3 of Fig. 2 with the side bearing removed; and Fig. 4 represents a modification, partly in plan and partly in section.

Similar letters of reference indicate similar parts throughout the several views.

Referring to the drawings, B indicates the journal-bar, which is preferably a single integral casting flanged above and below, as shown, and of greater depth at its middle 35 than at its ends, so as not only to afford a sufficient bearing for the transom channel-beams, but to constitute in itself an arch-bar.

The journal-bar B, as shown in Figs. 1, 2, and 3, may have integral plate-like projections or cheek-pieces b, to which the transom channel-beams I are secured by rivets or the like passing through the webs of the beams, and it is also preferably flattened and widened out at its ends between the pedestals to form 45 seats for the box-springs, or in lieu thereof, as shown in Fig. 4, the transom channel-beams may be secured to the journal-bar by separate angle-plates b', riveted in like manner to their webs and to the web of the journal-bar. I also 50 prefer to further brace and strengthen the structure by making the foundation-plate of the side bearing J integral with the part of

the upper flange of the journal-bar, as shown in Fig. 2.

F indicates a tie-bar which may directly 55 connect the pedestals or guide-columns D D for the axle-boxes E, as indicated in dotted lines in Fig. 1, but which is preferably arched at its middle portion, as shown in full lines in said figure, and riveted to the lower flange of 60 the journal-bar, thereby tying the pedestals to the journal-bar as well as to each other. The axle-box springs M are interposed in the usual manner between the axle-boxes E and the journal-bar and are adapted to be made 65 adjustable.

The pedestals D D extend between the journal-bar and tie-bar and are held in place by bolts G, which pass through the hollow interior of the pedestals and are secured above 70 and below the nuts, as shown. It is evident that an axle-box can be quickly removed by removing the corresponding outer bolt G and slipping the outer pedestal out from between the journal-bar and tie-bar, thereby permitting the like lateral removal of the axle-box and without disconnecting any other portions of the structure.

Having thus described my invention, what I claim is—

1. In a car-truck side frame, the combination of a journal-bar deeper at its middle than at the ends, a transom secured to said deeper portion, a tie-bar arched at its middle and secured to the deeper portion of the journal-bar, pedestals secured between the ends of the journal-bar and the downwardly-extending ends of the tie-bar, vertically-movable axle-boxes guided between the pedestals, and springs reacting between the ends of the journal-bar and the boxes.

2. In a car-truck side frame, a journal-bar, a transom connected to the inner side of the journal-bar, a tie-bar, said tie-bar being arched at its middle portion and attached thereto to 95 the lower flange of the journal-bar, pedestals between the tie-bar and journal-bar, vertically-movable axle-boxes guided between the pedestals, springs reacting between the ends of the journal-bar and the boxes, and means 100 for removably securing the outer pedestals in place; substantially as described.

3. In a car-truck side frame, the combination of a journal-bar, tie-bar, transom-beams,

pedestals secured between the ends of the journal-bar and those of the tie-bar, axle-boxes movable vertically between the pedestals, and springs reacting between the ends of the journal-bar and the boxes, the journal-bar having lateral flanges at its upper and lower edges between which the transom-beams are secured, and being flattened and widened out at its ends between the pedestals to form seats for the box-springs.

4. In a car-truck side frame, the combination of a journal-bar, tie-bar, channel transom-beams, pedestals secured between the ends of the journal-bar and those of the tie-bar, axle-boxes movable vertically between

the pedestals, and springs reacting between the ends of the journal-bar and the boxes, the journal-bar having inwardly-projecting lateral flanges at its upper and lower edges, the latter to form a seat for the transom-beams, ²⁰ and the former being extended inwardly to form a foundation for the side bearing of the car and a brace for the transom-beams.

In testimony whereof I affix my signature in presence of two witnesses.

EDWARD F. GOLTRA.
